PRESS WITH AUXILIARY CYLINDER CIRCUIT

Paul C. Pocock, Marion, Ohio, assignor to The Hydraulic Development Corp., Inc., Wilmington, Del., a corporation of Delaware

Original application June 7, 1938, Serial No. 212,327. Divided and this application August 11, 1939, Serial No. 289,680

8 Claims. (Cl. 100—71)

This invention relates to presses, and in particular, to arrangements for operating auxiliary rams in hydraulic presses.

One object of this invention is to provide a hydraulic press operating circuit, wherein an independent pressure-operated device, such as an auxiliary ram, is actuated by pressure fluid generated in response to the motion of one of the press plungers.

Another object is to provide such a circuit, wherein the auxiliary piston is actuated by pressure fluid trapped on one side of a double-acting piston connected to the press mechanism.

Another object is to provide such a circuit, wherein an auxiliary piston is hydraulically connected to one side of a double-acting push-back piston so as to be operated by the fluid entrapped and compressed on one side of this double-acting push-back piston.

This application is a division of my copending application, Serial No. 212,327, filed June 7, 1938.

In the drawing:

Figure 1 is a side elevation, partly in section along the axes of the push-back and auxiliary rams, of a hydraulic press operating circuit which actuates an auxiliary ram from fluid entrapped on one side of a double-acting push-back ram.

Figure 2 is an enlarged cross-sectional view of the valve of the press circuit shown in Figure 1.

In general, the hydraulic press operating circuit of the present invention includes a main ram and push-back rams supplied with pressure fluid from a pump through a four-way valve. The push-back rams are double-acting and one side of one or both of the push-back rams is connected to an auxiliary cylinder containing an auxiliary piston. In this manner, the auxiliary piston is actuated by pressure fluid supplied and generated as the result of the motion of the push-back rams in compressing the entrapped fluid.

Referring to the drawing in detail, Figure 1 shows a hydraulic press having an auxiliary piston, such as may be used for moving a die, actuated by pressure fluid generated as a result of the trapping of fluid on one side of a double-acting piston, such as a push-back piston. In particular, Figure 1 shows a hydraulic press having a bed 50, a head 51 interconnected by strain rods 52, upon the ends of which are threaded nuts 53, and a surge tank 54 mounted upon the head for supplying the working fluid, such as oil, by which the various circuits are actuated.

Within the press head 51 is a main cylinder

55 communicating through a port 56 with the interior of the surge tank 54. Mounted in the port 56 is a surge check valve 57, of the type disclosed in the Ernst Patent No. 1,956,758, of May 1, 1934, and forming no part of the present invention. This surge check valve 57 serves to prefill the main cylinder 55 as the main plunger 58 moves downwardly under the influence of gravity, and also is forcibly opened by fluid reaching it from the push-back circuit during the retraction stroke of the main plunger 58. The main cylinder 55, within which the main plunger 58 reciprocates, is closed at its lower end by an annular packing 59, compressed by a gland 60 to prevent leakage therefrom around the main plunger 58. The latter is connected to a platen 61, reciprocable relatively to the strain rods 52 and having a platen side arm 62 on either side thereof.

Connected to each lateral arm 62 is a push-back plunger 63 having a piston head 64 reciprocable within the push-back cylinder bore 65 within the push-back cylinder 66. The push-back cylinder bore 65 is closed by an annular cylinder head 67, with a packing 68 compressed by a gland 69 for the prevention of leakage. The bottom of the push-back cylinder bore 65 is provided with a port 70, from which a conduit 71 leads to the T 72 from which the conduits 73 and 74 lead to the push-back connection 75 of the reversible variable delivery pump 76. A branch conduit 77 leads to a check valve 78 within the surge tank 54. The check valve 78 opens inwardly in the direction of the pump 76, but closes outwardly in the direction of the surge tank 54.

The pump 76 is also provided with a forward connection 79 having a conduit 80 leading to the connection 81, having a port opening into the main cylinder 55 above the main plunger 58. Leading from the T 72 is a conduit 82 running around the press bed 50 to the bottom port of another push-back cylinder (not shown) similar to the push-back cylinder 66. The pump 76 is of the well-known reversible variable delivery type, with radial pistons and cylinders, and having a servomotor 83 for shifting the flow-control member or shift ring of the pump under the control of the servomotor valve rod 84. On the opposite side of the pump is a safety centering device 85 for bringing the shift ring back to its central or "no delivery" position in the event of stoppage of the driving motor, thereby preventing the coasting down of the main plunger under the influence of its weight. The details

of the servomotor 83, servomotor control valve rod 84 and safety centering device 85 are disclosed in the copending application of Walter Ernst, Ser. No. 170,250, filed October 21, 1937, now matured into Patent No. 2,184,665, dated December 26, 1939, and form no part of the present invention.

Pivots connected to the outer end of the valve rod 84 is a lever 86, pivoted as at 87 on the swinging link 88, which in turn, is pivoted at 89. Pivots connected to the lever 86 is a connecting rod 90, the opposite end of which is pivots connected to one arm of the bellcrank 91, to the opposite arm of which is pivots connected the connecting rod 92. The lower end 15 of the connecting rod 92 is pivots connected to one arm of the bellcrank 93, to the opposite arm of which is pivots connected the connecting rod 94. The left-hand end of the connecting rod 94 is pivots connected to the bellcrank 20 arm 95 of a lever 96, which is pivots mounted upon the jack shaft 97. Pivots connected to the right-hand end of the lever 96 is an armature rod 98, connected at its lower end to the armature 99 of the solenoid 100. The left-hand 25 end of the lever 96 is yoke-shaped, with rounded portions 101 engaging an adjustable collar 102 on opposite sides of the main control rod 103. The latter is reciprocably mounted in the bosses 104 and 105 extending outwardly from the press 30 head 51 and bed 50, respectively.

Mounted upon the press head 51 is a limit switch 106, forming a part of the electrical circuit containing the solenoid 100 and actuated by the conical cam 107 upon the main control 35 rod 103. The latter likewise carries collars 108 and 109, surrounded by and adapted to be engaged by the arm extension 110 projecting forwardly from the platen side arm 62. The engagement of the arm extension 110 with the collar 108 on the upward stroke of the platen 61 lifts the main control rod 103 to shift the servomotor control valve rod 84, and consequently the pump shift ring, to their neutral positions for halting the upward motion of the platen 61. On the other hand, the engagement of the arm extension 110 with the collar 109 on the downward stroke of the platen 61, operates the main control rod 103 in a downward direction to shift the servomotor control valve rod 84 to its reversed position, thereby moving the shift ring of the pump 76 to its reverse delivery position so as to cause the beginning of a retraction stroke of the main plunger 61 by supplying pressure fluid through the conduits 71, 73, and 74 leading to the push-back cylinders 66.

The main control rod 103, near its lower end, carries a pair of spaced collars 111 engaging the rounded yoke ends 112 of a lever arm 113 pivots mounted on the jack shaft 114, which in turn, is mounted upon the bed 50 of the press. Secured to the lever arm 113 and forming, in effect, the second arm of a bellcrank, is the hand lever 115. By manipulating this hand lever 115 in opposite directions, the main control rod 103 may be lifted or depressed to operate manually the servomotor control valve rod 84, thereby controlling the setting of the variable delivery pump 76.

The arrangement according to Figure 1 is 70 adapted to actuate an auxiliary piston or ram for operating any suitable device. For purposes of example, Figure 1 shows this device to consist of a die holder 116, which is slideable to and fro across the bed 50 by means of a connecting

rod 117 having a crosshead 118 thereon, the lower end of which slides in guideways 119. The die holder 116 is suitable for carrying a die of any desired form so as to move the die into and out of position beneath the platen 61. Such die holders or sliding tables 116 are known to those skilled in the art, as well as the various kinds of dies utilized therewith, depending upon the nature of the workpiece. Accordingly, the details thereof form no part of the present invention, and a disclosure of a conventional form will be found in the patent to Ernst No. 2,009,487, dated July 30, 1935. For so moving the die holder 116 the connecting rod 117 is threaded at its outer end 120 to carry a pair of nuts 121, between which is secured a yoke 122, the lower end of which is secured between the nuts 123 threaded on the outer end 124 of the auxiliary piston rod 125. The latter carries a piston head 126, reciprocable within the cylinder bore 127 of the auxiliary cylinder 128, the latter being carried by the bracket 129, which also supports the guideways 119 and is in turn secured to the side of the press bed 50.

The auxiliary cylinder 128 is closed by an annular cylindrical head 130, having a packing 131 compressed by a gland 132 to prevent leakage. The right-hand end of the auxiliary cylinder 128 is provided with a port 133 having connected thereto a conduit 134 leading to the T 135 upon the conduit 73, and communicating with the latter. The auxiliary cylinder 128 at its opposite end is provided with a port 136, to which is connected the conduit 137 leading to the port 138 in the push-back cylinder 66 above the uppermost position of the piston head 64.

Leading from the port 138 and connected to the conduit 137 is a conduit 139, leading to the port 140 of the auxiliary control valve, generally designated 141. The latter consists of a casing 142 with a bore 143, reciprocably containing the valve member 144 having the spaced valve heads 145 and 146. Connected to the valve member 144 is the auxiliary valve control rod 147, having thereon spaced collars 148 and 149, respectively, adapted to be engaged by the platen arm 150 projecting outwardly from the platen 61. The auxiliary valve control rod 147 passes outwardly from the casing 142, through the annular casing head 151. The lower end of the valve member 144 terminates in the reduced diameter valve rod extension 152, leading downwardly through the spring casing 153, secured to the valve casing 142, and into the socket 154. The spring casing 153 contains a spring chamber 155 inclosing a coil spring 156, surrounding the valve rod extension 152 and engaging a collar 157 slidably mounted on the valve rod extension 152. When the valve member 144 is moved downwardly a sufficient distance, the annular shoulder 158 between the valve member 144 and the valve rod extension 152, engages the collar 157, pushing the latter downwardly and compressing the coil spring 156. The valve casing 142 is provided with a passageway 159 leading to spaced ports 160 and 161 opening into the annular enlargements 162 and 163 of the valve bore 143. Opening into the passageway 159 is a port 164, to which is connected the conduit 165 leading upwardly to the interior of the surge tank 54.

In the operation of the circuit shown in Figure 1, the pump servomotor control valve 84 is shifted either manually, by moving the hand lever 115, or electrically by energizing the solenoid 100 so as to place the pump shift ring in its forward

delivery position. In this position the pump 76 delivers pressure fluid through the connection 79 to the conduit 80, and through the connection 81 into the main cylinder 55 above the main plunger 58. The latter moves downwardly, aided by gravity, and the space it leaves is prefilled by means of the automatically opening surge check valve 57. Fluid thereby passes through the port 56, from the surge tank 54, into the top of the main cylinder 55. The descent of the main plunger 58, and the consequent descent of the platen 61, causes the descent of the push-back plungers 63 and their piston heads 64 within the cylinder bores 65 of the push-back cylinders 66. The fluid beneath the push-back piston heads 64 is discharged through the ports 70 and the conduits 71 and 82, into the conduits 73 and 74, and thence into the push-back connection 75 now constituting the suction side of the pump 76.

As the push-back piston heads 64 are moved downwardly, the suction created above them draws fluid into the tops of the push-back cylinder bores 65, through the conduit 139, the still open auxiliary control valve 141 and the conduit 165 leading to the latter from the interior of the surge tank 54. The valve heads 145 and 146 remain in their raised positions, shown in Figure 1, even after the platen arm 150 has disengaged itself from the collar 149 because of the friction of the packing surrounding the auxiliary valve control rod 147 beneath the valve casing head 151. As the platen 61 and main plunger 58 near the end of their downward strokes, the platen arm 150 engages the lower collar 148 upon the auxiliary control rod 147, and pushes the valve member 144 and the valve heads 145 and 146 downwardly through the closed position of the auxiliary control valve 141, into a second open position thereof. Meanwhile, the annular shoulder 158 has engaged the sliding collar 157 and compressed the coil spring 156. In this, the lowermost position of the valve 141, the port 140 is in communication with the ports 161 and 164 across the valve bore 143, because the valve piston head 146 has descended beneath the port 161. Thus, the valve 141 in its lowermost position still permits fluid to pass freely between the conduits 139 and 165.

The pump and press control system are then reversed in any suitable way, either manually by the operation of the hand lever 115, or automatically by a pressure-responsive switch 170 operated by the hydraulic motor 171 on the press head 51 or position-responsive switch 172 on the bracket 173 and engageable by the platen arm 62, in either case deenergizing the solenoid 100. This causes the shifting of the main control rod 103 and the servomotor valve control rod 84, with the result that the servomotor 83 moves the shift ring or flow-control member of the pump 76 over to its reversed position. In this position the connections 79 and 75 become, respectively, the suction and pressure connections of the pump 76. Fluid is therefore drawn from the main cylinder 55 above the main plunger 58, through the connection 81, conduit 80 and pump connection 79, into the pump 76, from whence it is discharged as pressure fluid through the connection 75, the conduits 74, 73 and 71 and 82, into the push-back cylinder bores 65 beneath the push-back piston heads 64, causing the latter to move upwardly.

The platen 61 consequently moves upwardly, and after it has moved a short distance, the platen arm 150 disengages the collar 148, where-

upon the coil spring 156 and sliding collar 157 engage the annular shoulder 158 and push the valve member 144 and the auxiliary valve control rod 147 upwardly until the collar 157 engages the top of the spring chamber 155, and temporarily halts the upward movement of the valve member 144. At this point the valve heads 145 and 146 come to rest between the ports 160 and 161, shutting these off from communication with the port 140 and hence closing the valve 141 in its mid-position. The reason for allowing the platen 61 to move upwardly a short distance before closing the auxiliary control valve 141 is to insure that the die upon the die holder 116 is relieved of the pressure of the platen before any motion of the die holder 116 is brought about.

When the auxiliary control valve 141 closes in this manner, the fluid is trapped in the line 139 and hence cannot any longer be discharged through the valve 141 and conduit 165, into the surge tank 54. Accordingly, this fluid trapped above the upwardly moving push-back piston head 64 passes downwardly through the conduit 137, into the left-hand end of the cylinder bore 127, causing the die-moving piston 126 with its yoke 122, connecting rod 117 and die holder 116, to move to the right into the retracted position thereof, out from beneath the central position thereof. The effective area of the piston head 126 is, of course, only equal to the area of the piston rod 125 because push-back pressure from the line 73 at that time is standing in the right-hand end of the auxiliary cylinder bore 127 because of the connection of the conduit 134 thereto.

When the platen 61 nears the top of its retraction or push-back stroke, the platen arm 150 engages the collar 149 and moves the auxiliary valve control rod 147 upwardly so that the valve member 144 and the valve heads 145 and 146 are moved into the upper open position of the auxiliary control valve 141. When the valve heads 145 and 146 reach these uppermost positions, the ports 140 and 160 are again in communication across the auxiliary valve bore 143, as shown in Figure 1. With the valve 141 in this position, fluid escapes through the conduits 137 and 139 from the ends of the cylinder bores 127 and 65, respectively. This permits the pressure fluid reaching the right-hand end of the auxiliary cylinder bore 127, through the port 138 and conduit 134 from the conduit 73, to push the auxiliary piston head 126 to the left and move the die holder 116 back into its working position centrally beneath the platen 61. Meanwhile, the platen arm extension 110 of the platen arm 62 has engaged the collar 108 upon the main control rod 103 and shifted the servo-motor control valve rod 84 to its neutral position, thereby moving the shift ring of the pump 76 to its neutral delivery position and halting the upward travel of the main plunger 58 and platen 61.

The foregoing illustration in the embodiment shown in Figure 1 merely shows the operation of a die carrier by means of fluid supplied from one of the push-back cylinders. It will be seen, however, that this arrangement is adapted to operate other devices than die holders, the latter being shown merely as an example. In a hydraulic press it is frequently advantageous to incorporate such a pressure-actuated device for performing some independent function, such as indexing a movable die holder, as shown in Figure 1, or for removing or feeding workpieces, etc. Motions of this nature must always be accurately

timed with the movements of the main ram, and follow in proper sequence therewith. Ordinarily, however, where two pressure-actuated pistons are located in separate cylinders, each performing a different work but open to the same pressure source, there is no certainty that both pistons will move in a desired sequence. One piston may move before the other, both may move together, or one may move part way and then the other, depending upon the resistance encountered as compared to the respective areas of these pistons.

In the present invention, however, the pistons must operate in the proper sequence because the pressure fluid for actuating the second piston is obtained directly as a result of the movement of the first piston. Thus, the fluid trapped upon one side of the double-acting press piston is conducted to the auxiliary piston to cause its operation in precisely the predetermined sequence, and without any possibility of deviation from this sequence.

It will be understood that I desire to comprehend within my invention such modifications as come within the scope of the claims and the invention.

Having thus fully described my invention, what I claim as new and desire to secure by Letters Patent, is:

1. In a hydraulic press circuit, a main plunger, a secondary plunger operatively connected with said main plunger, an auxiliary hydraulic motor hydraulically connected to said secondary plunger, hydraulic means for moving said secondary plunger and said auxiliary motor, means for discharging fluid from the motor-connected side of said secondary plunger selectively to said motor or to an exhaust, valve means disposed between said secondary plunger and said discharging means for controlling communication between said plunger and said discharging means, and control means adapted in response to the motion of said secondary plunger to close said valve means to cause said secondary plunger to create and convey fluid pressure, to said auxiliary motor for operating the same in one direction, said control means also being adapted to open said valve for establishing communication between said motor connected side of said secondary plunger and said exhaust to cause said hydraulic means to operate said auxiliary motor in the opposite direction.

2. In a hydraulic press circuit, a main plunger, a double-acting secondary plunger operatively connected with said main plunger, an auxiliary double acting piston having one side hydraulically connected to one side of said secondary plunger and the other side hydraulically connected to a pressure fluid source, means for discharging fluid from the motor-connected side of said double acting piston, valve means disposed between said double-acting piston and said discharging means, means movable concomitantly with the movement of said double acting piston for closing said valve means to cause said piston to create and convey fluid pressure in response to its movement to said auxiliary motor for operating the same.

3. In a hydraulic press circuit, a main plunger, a double acting push-back plunger connected thereto, an auxiliary hydraulic plunger, a hydraulic circuit interconnecting both sides of said push-back plunger with said auxiliary hydraulic plunger, a source of pressure fluid for selectively supplying pressure fluid to said main

plunger or to one side of said push-back plunger, control means for selectively entrapping or releasing fluid on the opposite side of said push-back plunger, and means responsive to a predetermined motion of one of said plungers for causing said control means to entrap said pressure fluid, whereby this pressure fluid is caused to pass to said auxiliary plunger for operating the same after the push-back plunger has moved a predetermined distance.

4. In a hydraulic press circuit, a main plunger, a double acting push-back plunger connected thereto, an auxiliary hydraulic plunger, a hydraulic circuit continuously interconnecting both sides of said push-back plunger with opposite sides of said auxiliary hydraulic plunger, valve means for conveying fluid from one side of said push-back plunger selectively to one side of said auxiliary plunger or to an exhaust, a fluid source for selectively supplying pressure fluid to said main plunger onto said push-back plunger, means responsive to a predetermined position of one of said plungers during the return stroke of said main plunger for causing said valve means to direct pressure fluid from said one side of said push-back plunger to said auxiliary plunger for causing said auxiliary plunger to perform a stroke in one direction, and means responsive to another predetermined position of one of said plungers during the return stroke of said main plunger for causing said auxiliary plunger to return to its previous position.

5. In a hydraulic press circuit, a main plunger, a double acting secondary plunger operatively connected with said main plunger, a fluid source for supplying pressure fluid selectively to said main or said secondary plunger, an auxiliary double acting piston having its opposite sides connected respectively to said secondary plunger and said fluid source, and means responsive to the movement of said main plunger for controlling hydraulic connection between said secondary plunger and said auxiliary piston, and between the latter and said fluid source to positively move said auxiliary plunger in two opposite directions, while said main plunger moves in one and the same direction.

6. In a hydraulic press circuit, a main plunger, a double acting push back plunger operatively connected with said main plunger, a source of pressure fluid for selectively supplying pressure fluid to said main plunger or to said push back plunger for respectively advancing or retracting said main plunger, an auxiliary plunger hydraulically connected with both sides of said push back plunger, and means responsive to the travel of said main plunger during the movement thereof in one and the same direction for sequentially causing fluid expelled by one side of said push back plunger to move said auxiliary plunger in one direction, and pressure conveyed by the pump to the opposite side of said push back plunger to move said auxiliary plunger in the opposite direction.

7. In a hydraulic press circuit, a main plunger, a push-back plunger connected thereto, an auxiliary hydraulically operable piston, conduit means hydraulically interconnecting said push-back plunger with said piston, valve means having two spaced open end positions for releasing fluid from one side of said push-back plunger to an exhaust, and also having an intermediate closed position for preventing fluid to escape from said one side of said push-back plunger to said exhaust, a fluid source for supplying pressure fluid selectively to the main plunger or to the

opposite side of said push-back plunger, and control means responsive to a predetermined motion of one of said plungers for moving said valve means from one of its open end positions into its intermediate closed position to entrap the pressure fluid between said first mentioned side of said push-back plunger and said valve means, whereby this pressure is caused to pass to said auxiliary piston for operating the same in response to the travel of one of said plungers in one direction.

8. In a hydraulic circuit, a main plunger, a push-back plunger operatively connected to said main plunger and having a first area and an opposed second area, a fluid source for supplying pressure fluid selectively to said main plunger or to said first area of said push-back plunger for reciprocating said main plunger, a fluid operable piston with a first area and an opposed greater second area, conduit means for hydraulically interconnecting said first areas and for establish-

5 ing hydraulic communication between said second areas, valve means having two spaced open end positions for establishing hydraulic connection between the second area of said push-back plunger and an exhaust, and also having an intermediate closed position for entrapping fluid between said second areas, and control means operatively connected with one of said plungers and responsive to the supply of pressure fluid to the first area of said push-back plunger and the movement of the latter caused by said fluid to first move said valve means from one open end position into said intermediate position, to cause fluid entrapped between said second areas to move said piston from a first position into a second position, and thereafter to shift said valve means from said intermediate position to the other end position to cause said piston to return to said first position.
